UNITED STATES PATENT OFFICE.

DANIEL SCHUYLER, OF SAN DIEGO, CALIFORNIA, ASSIGNOR TO THE PERFECT SLIDING DOOR COMPANY, OF LOS ANGELES, CALIFORNIA, A CORPORATION OF CALIFORNIA.

SEMI-METALLIC WALL STRUCTURE FOR SLIDING DOORS.

No. 851,780.

Specification of Letters Patent.

Patented April 30, 1907.

Application filed February 18, 1905. Serial No. 246,324.

To all whom it may concern:

Be it known that I, DANIEL SCHUYLER, a citizen of the United States, a resident of San Diego, in the county of San Diego and 5 State of California, temporarily residing at Bridgeport, in the county of Fairfield and State of Connecticut, have invented a new and useful Semi-Metallic Wall Structure for Sliding Doors, of which the following is a 10 specification.

This invention is an improvement in a wall structure heretofore invented jointly by Homer Laughlin Jr., and myself and set forth in our application for Letters Patent of 15 the United States, filed July 25, 1904, Serial No. 218,060 which so far as I am aware sets forth the pioneer steel structure for purposes of this kind and which application contains basic claims dominating the invention set 20 forth in this application.

This invention is particularly designed for increasing the perfection of the system of sliding doors known as the perfect sliding door system.

An object of this invention is to improve 25 the invention set forth in said joint application by increasing the strength and rigidity of portions thereof without increasing the cost and without greatly adding to the weight 30 of the structure, and at the same time making improved provision for fastening to the metal portion of the structure, the timbers of wood or other material which require to be fastened thereto in completing the wall 35 for practical use.

Another object of the invention is to so construct the wall structure having a pocket 40 for a sliding door, as to avoid any liability of injury from shrinking, warping or twisting of any wooden portions which may be applied 45 in completing the structure.

This invention is designed to be embodied 50 in a structure, the skeleton or main frame of which is principally or mainly of sheet steel or other sheet metal reinforced and supplemented to a greater or less extent by parts made of wood or other suitable material.

An object of this invention is to provide a 55 structure for the wall pockets and doorways of sliding doors which can be finished with narrower casings than has heretofore been possible with sliding doors; also to make provision for the most ready and convenient

manner of fastening the timbers and exterior finishing parts such as the casings, jamb 55 and stops to the metallic frame of the structure.

Another object is to provide a sliding door pocket structure of superior rigidity smoothly lined on the inside and adapted to wooden 60 and metallic lath indiscriminately. In this connection the invention includes the combination with the wall-pocket frame, of fluted siding which is preferably matched or tongued and grooved and which may be fastened to the frame with the flutes or channels running diagonally, horizontally or vertically, the diagonal arrangement being deemed preferable for the wooden lath and the horizontal arrangement for metallic lath. 70

An object of this invention is to bring into one solid, firm and practically unitary structure all of the elements essential for the installation and the maintenance in operative condition of any of the closures of the perfect 75 sliding door system; provision being made whereby said structure, though originally constructed for the gravity closing sliding door, can by the removal of certain parts be adapted for the reaction closed door or any 80 other form of door of said sliding door system; provision also being made for adjustment of the rail of said structure, both as to height, inclination and tension, also providing for 85 most ready removal and replacement of said rail; and also to improve the structure over other forms in particulars which will herein-after be more fully detailed.

The invention is applicable in the construction of wall pocket structures for both 90 single and double doors.

Another object is to provide a semi-metallic door-pocket wall-structure in which a greater or less number of the metal parts may be applied with other portions made of wood 95 or other material instead of metal to form substantially the same mechanically effective structure, so that the metal portions of a structure having a wholly metallic frame and of a structure having a frame partly of metal 100 and partly of some other material may be made with the same set of rolls and dies. That is to say, with this invention it is not necessary to construct the entire frame of steel; although that character of structure is 105 deemed preferable, except where the user

may prefer for economical or other reasons to make the structure partly of wood or other material.

Another object of the invention is to provide a sliding door structure adapted for use inter-changeably for the gravity closed door having an inclined rail, and for the doors having a horizontal rail.

Another object is to provide improved means for mounting the rail at both ends of the structure and giving greater stability to the rail and supports in said system than has heretofore been possible.

A further object is to provide means by which the rail can be easily taken out of the structure and replaced at any time; which has heretofore been impossible without destroying portions of the wall and other parts of the structure.

Another object is to provide means for adjusting the cantaliver pressure to the rail after the closure is mounted, without removing any part or parts whatever of the structure, closure, or fixtures. Heretofore this has been impossible.

Another object is to provide for greater up and down adjustments of the rail than has heretofore been possible.

Another object is to make accessible the center brackets and hangers where double doors are used, to such an extent that they can be quickly and easily taken out or replaced.

A further object of the invention is to so construct the structure as to insure the appropriate mounting of the same and to avoid the liability of misassembling or misarrangement of the parts, frequently occurring through ignorance or malice of carpenters in installing the former wooden structures.

Another object is to provide for the right construction and economical application of various parts to the structure by means of which the rail supports or brackets of said structure may be adjustably mounted therein in the simplest, most efficient and satisfactory manner, and so as to insure the highest accuracy of exact positioning and the utmost certainty of maintaining true position.

Another object is to provide maximum adjusting space for adjusting the closure toward and from the rail with minimum depth of header, an object being to allow the closure to be raised to leave space for a rug when it is desired to place a rug over the threshold; or to bring the closure down close to the bare floor when so desired.

An object of this invention is to make provision whereby the trade may be furnished with a semi-metallic wall structure for sliding doors, of different grades, in some of which the frame of the structure will be entirely metallic and in others of which wood or some other material will be substituted for

parts of the frame which will ordinarily be of metal. I purpose in some instances to substitute a wood back-post and a wood front door-post for the back-post and front door-post which by preference will usually be partly or wholly composed of metal.

Another object of the invention is to so construct the sliding door structure as to enable any workman to readily insert and remove the rail at any time before or after the house is completed and also bring the rail to the rigid, firm and stable condition required of the rails in the perfect sliding door system.

Another object is to make provision for giving a greater or less thickness of wall with a single thickness and style of steel frame.

Another object is to provide an improved mounting for the buffer spring of the reaction closed door of said perfect sliding door system.

Another object is to provide an improved mounting for the cantaliver rail brackets and at the same time provide for tying together, stiffening and strengthening the frame.

Another object is to provide for mounting the rail brackets adjustably at the slightest expense.

Another object is to avoid a difficulty which has heretofore existed in said perfect sliding door system to wit:—It has been found that with the character of screens heretofore employed to form the side walls of the slots in which the bolts for supporting the closures move, the workmen were liable in installing the structure to so construct and mount said slot-screens that they would interfere with the door hanger, thus preventing the smooth anti-friction movement of the closure which is characteristic of the doors of this system when properly installed. For the purpose of avoiding such difficulty and of attaining various other advantages, I provide a novel slot-screen in the form of a thin metallic blade which is preferably provided with a flange, the blade and said flange being formed as an angle iron and the flange being provided with perforations through which nails or screws may be inserted for the purpose of fastening the screens to the head jamb.

With the previous forms of door structure with which I am acquainted there is liability of injury to the same by careless and wrong handling of the closure in installing or adjusting the same. An object of this invention is to provide against accidents of this nature and to make it more convenient for repairing any damage which may be done in this way. This I accomplish by constructing a metallic screen in the form of a thin blade as above stated and fastening the same to the inside of the head jamb. Said metallic screens are to be manufactured and carried in stock and while thin yet of such thickness

that they will withstand considerable hard usage without danger of being bent or damaged.

Another object is to provide for the ready insertion and removal of the slot screen in order to gain access to the cavity in which the hanger and other closure supporting parts are contained.

Another object of the invention is to make provision whereby the automatic gravity closed door of said perfect sliding door system can be installed in ordinary rectangular form, rising as it ascends the rail in the act of opening, and falling as it approaches the jamb in closing; said screen allowing said movement of the closure to take place without interference from the screen and yet allowing the visible portion of the screen at the edge and top of the closure to maintain the same apparent relation to the closure at all times. Heretofore it has been necessary to make the top of the closure aslant to correspond with the slant of the rail in order to avoid interference of the screen with the movement of the closure, and yet allow the top front edge of the closure to be at all times appropriately near the screen.

By this invention it is possible to mount the top of the closure very close to the screen and to leave the space between the screen and the top of the closure uniformly-small at every point to which the closure may be brought.

The screen is applicable on both sides of the closure way; the construction on each side being substantially like that on the other, and consists in the head jamb and the other parts thereof hereinafter described and claimed.

Another object is to so construct and arrange the structure as to avoid visible offsets below the screens.

Another object is not only to provide against mistakes of ignorant workmen in the installation of said perfect sliding door system with relation to the screens which form the side walls of the slots in which the suspending bolts that carry the closure run; but also to provide for more ready detachment and attachment of such screens to the head jambs of the door structure, and also to provide one form of screen which can be readily and easily applied to all forms of sliding doors of said system. By this portion of the invention the workman is enabled to apply a slanting screen to the face of the jamb for a gravity closed door, thus avoiding the necessity of cutting the top of the closure aslant when installing the same as a gravity closing door. That is to say, with the constructions heretofore in vogue in said system, it was necessary in installing gravity closing doors that the top end of said door should slope to correspond with the slope of the rail while the body of the closure remained vertical. In

my novel structure the slot screens are made of thin strong sheet metal, preferably in the form of angle-iron one of the flanges of which is perforated for receiving screws or nails by which to be fastened to the inner face of the head jamb.

An object is to provide for fastening said metallic screens to the head jambs in such a manner as to conceal from view the means of fastening.

The accompanying drawings illustrate the invention.

Figure 1 is a fragmental side elevation of a semi-metallic wall structure embodying this invention in a form in which the end posts 8c and the mouth posts are constructed with a metal frame fastened to the metal header; and the siding that forms the lining for the plastering is constructed of matched and fluted boards set diagonally in the wall with horizontal lathing over the diagonal fluting. Fig. 2 is a plan on line II-II, Fig. 1, omitting the siding from the front side of the structure. Fig. 3 is a fragmental detail of such structure, omitting some portions for clearness of illustration. Fig. 4 is a sectional view taken through the doorway and looking left from line IV-V in Fig. 3, omitting portions. Fig. 5 is a fragmental sectional view taken through the doorway looking right from line IV-V in Fig. 3. Fig. 6 is a contracted fragmental sectional view taken from the line VI at the right of the mouth posts in Fig. 3 looking left. Fig. 7 is a fragmental plan showing the lower metal portions of the posts. Line VII, Fig. 3, indicates the line of the section. Fig. 8 is a fragmental mid-section of that portion of the structure which affords support for the front end of the rail. Fig. 9 is a view of said portion from the right. Fig. 10 is a fragmental sectional detail of the portion of the structure which supports the rear end of the rail. Fig. 11 is a view of the same looking from the mouth of the wall pocket toward the back post. Fig. 12 is a view of said portion omitting the bracket. Fig. 13 is a view of said portion with bridge removed for use with horizontal rail. Fig. 14 is a section on line XIV, Figs. 8 and 9. Fig. 15 is a section on line XV, Figs. 10 and 11. Fig. 16 is an elevation of a portion of the structure showing the arrangement of the head timber, head jamb and slanting screen for a gravity closing sliding door. A fragment of the door closure is also shown in this view to illustrate the advantage gained by this novel structure. Fig. 17 is a fragmental elevation showing a metal screen on the head jamb and arranged for a re-action closed door or other form of horizontal sliding door. Fig. 18 is a view of the metal head-screen detached. Fig. 19 is a fragmental cross-section showing the metal screen and other parts of the structure as arranged for a gravity closing door. A fragment of a closure and its

hanger is shown. Fig. 20 is a view showing joined fluted boards for the siding. Fig. 21 is a view of the blank for forming the body of the back bracket support.

- 5 In the present invention certain members of the structure may be designated in a general way as follows:—A, front door post; B, back or rear post; C, header; D, mouth posts; G, iron stays.
- 10 1, 2, 3 are external sheet metal frame members made of channel iron, preferably sheet steel, to form a portion of the front and back posts and header, respectively, of the structure. 4, 5 respectively designate in a general way means at the junctions of said header and said posts for supporting rail brackets which are designated in a general way by the characters 6, 7; said supporting means being fastened to the header 3 and to 15 their posts 1, 2 respectively and tying said header and posts together; and each of said bracket-supports 4, 5 being provided at the lower end with a projection for supporting its bracket. Said projections are designated 20 respectively by the characters 8 and 9. 10 is a loop at the upper portion of the back bracket support, and 11 a bridge on the supporting projection 9 of said bracket support. The back cantaliver bracket 7 for supporting 25 the rail 12 has a base 13 which extends above and below its bracket arm 14; the upper extension 15, of said base being provided with a perforation in the form of a slot 16 and the lower extension 17 being interlocked with 30 said bridge 11 by means of a boss 18 and seat 19 on the bridge and lower extension. 20 is a fastener in the form of a rivet extending through the loop 10, the upper extension 15 of the base, the back bracket support 5, and 35 the channel iron 2 of the back post. The cantaliver bracket 6 for the front post, is provided with a base having extensions 21, 22 above and below its bracket arm 24; the lower extension 22 having a vertical screw 40 hole 23. An adjusting screw 25, having collars 26 engages in a slot 27 with the lower projection of the front bracket support, and screws into the screw-hole 23 in the lower extension 22 of the front bracket 6 to raise and 45 lower said bracket.
- 50 28 is a loop fastened to the front bracket support 4 and through this the upper extension 21 of the front bracket 6 moves so that as the screw 25 is turned, the front bracket 55 will be raised or lowered.
- 29 is a rail socket in the back bracket; the same being lower than the top of the outer end of the back bracket when the base of said bracket is upright, so that when the rail 12 is 60 resting on the inner or back cantaliver arm 14 and has its back end inserted into the rail socket 29 and its front end brought over and down toward the cantaliver arm 24 of the front bracket, it will be engaged at top and 65 bottom by, and thereby cramped firmly in

the bracket, but can be readily withdrawn and reinserted by simply lifting the front or outer end and then moving the rail endwise.

30 is a stirrup extending over the end of the rail which is above the front bracket arm 70 and 31 is a set-screw, screwed through said stirrup and into a seat 32 in the bracket arm 24, so as to draw the front end of the rail downward by pressure on the top thereof. Said bracket arms 14 and 24 are slanted upward 75 toward each other with an open space between the front brackets and the end of the rail so that when the screw 31 is tightened, it will tend to bow the rail by straining it over the tips of the cantaliver arms, and will thus 80 bring the rail and the several parts of the structure hereinbefore enumerated into tension.

By the means above described it is made possible to insert, remove and reinsert and 85 adjust the rail at pleasure.

It is to be noted that the screw 31 engages the under face of the bracket and is below the bracket and readily accessible and that by this construction the trough-shaped rail 12 is 90 fastened in place, although it chambers the bracket.

33 is a U shim of spring wire springing in between the side walls of the back bracket support above the rivet 20 between the upper extension of the back bracket and its support to bring the outer end of the cantaliver arm 14 downward slightly below where it would otherwise stand when the bridge 11 is used as shown in the drawings; thus to 100 avoid the necessity of producing too great tension in the rail when said rail is arranged in its slanting position for the gravity closing sliding door. That is to say, the cantaliver arms of the brackets are inclined upward at 105 an acute angle with the upper extension of the base of the bracket, and the rail socket 29 is arranged in such position relative to the bracket arm 14 that when a straight rail is simply rested on the arm and its end is 110 inserted into the socket 29 said rail will extend almost on a level; but will have a slight upward slant outwardly, so that when its other end is brought down to a level, there will be a slight tendency to arch produced in 115 the rail thus to give superior supporting quality to the rail.

The stirrup 30 and its set screw 31 on the end of the rail engaging the under-side of the front bracket arm enables the workman to 120 accurately adjust the tension of the rail so that if the weight of the closure should be sufficient to cause a sagging deflection of the rail at its middle, such sagging may be remedied by screwing the screw 31 tighter, and 125 vice versa.

The rail may be adjusted as to level or inclination by adjusting the collar set screw 25.

It is obvious that when the tips of the bracket arms are in the same horizontal 130

plane, less tension will be given the rail upon bringing its front end down into position on the front bracket while the rear end is cramped by the rear bracket than would be given by bringing said front end to the same position when the rear bracket is upheld by the bridge 11 as shown in the drawings. Consequently, when it is desired to use the same fixtures for mounting the door and yet mount it as an ordinary horizontal sliding door or as a re-action closed door in which the rail is mounted practically horizontally, it becomes desirable to lower the bracket 7, then the bridge 11 and the shim 33 must be removed, or which is just the same, should be omitted from the structure.

34 is a timber fastened by screws or nails 35 in the channel of the front post channel-iron, 1. K is a block fastened to the upper portion of said timber by screws 36. To this block, the front bracket support 4 is fastened by screws 96. 37 is the jamb against which the closer, I, shuts. Said jamb appears in Figs. 8, 9 and 16. It is fastened on the timber 34 and fitted below the bracket block K.

38 is a cleat fastened by rivets 39 to the channel-iron 3 of the header and serving together with block K, which it engages, the 39 jamb timber 34, fastened in channel iron 1, screws 36 and 96, loop 28, rivets 40 and the rail bracket 6, and its adjuncts such as stirrup 30, to complete the means which unite the rail and the members of the external 35 frame in a rigid unitary structure.

41 is a plate which forms the main body of the front rail bracket support. Its upper end engages the cleat 38 and fits between the sides of the loop 28 which slidably holds the 40 upper extension 21 of the front rail bracket 6.

42 designates metal ties connecting the end posts 1, 2, together below the channel-iron member 3 of the header. 43 designates sheet metal mouth posts on opposite sides of the structure, respectively fastened to said ties 42 and to the head 3.

44, 45 and 46 designate ties connecting the mouth posts respectively to the back post.

47 designates re-inforcing sheet metal strips fastened to the mouth posts and provided with projections 48 extending transversely of the posts; said mouth posts and strips being perforated and timbers 49 provided for completing the mouth posts; the 55 same being held by said projections and by nails or screws 50, 51 driven through the stop 81, through said mouth posts and re-inforcing strips into said timbers. The transverse projections 48 form solid braces for strengthening the post. The strips 47 are desirably formed of flat strap iron bent over at the ends, thus to form the braces in a simple and effective way without interfering with the placing of the timbers.

65 The lower channel-iron tie 46 has its chan-

nel upper-most and the upper channel-iron tie 44 has its channel downward. 52 designates longitudinally grooved siding fastened in place in said channels and against said timbers 49 which may or may not be extended by furring 53.

54 designates brackets on the door-way side of the mouth posts, and 55, brackets on the outer faces of the front post. F designates the head timber mounted in said brackets on opposite sides of the frame.

56 designates the head jambs fastened to the timbers F. 57 designates sheet metal slot screens for said head jambs respectively, each comprising a metal plate fastened to 80 and extending inward from its head-jamb 56 to form together a narrow slot extending along the mid-line of the rail.

58, 59, 60 and 61 designates anchor-plates extending across the bottom of the structure 85 frame and connecting the mouth post and lower channel tie of one side of the structure with those on the other side of the structure.

It is very important that the closure-supporting rail of a sliding door structure 90 shall be mounted with perfect central true-ness in order that the closure can move in a cavity of minimum dimensions without li-ability of rubbing. The rail 12 shown is a sheet metal rail of an approximately trough 95 shape; the same being described and claimed in an application filed by Homer Laughlin Jr., and myself, June 18, 1904, Serial No. 213,121. In order to secure this absolute centering of the rail it is necessary to provide 100 means by which the workman will be com-pelled to properly locate the rail bracket supports and this is done by means of the loops 10 and 28, one of which accurately fits into the back bracket support and over 105 and against the sides of the upper extension of the back bracket and between the same and the side walls of the back bracket sup-port, and the other of which is used to clasp and centrally locate the front bracket exten-sion. The rivet 20 for the back bracket is 110 riveted through the bracket support and the back steel post or frame. The loop 28 is used to center and firmly clamp the upper extension of the front post bracket and is 115 riveted by rivets 40 to block K, which in turn is screwed fast to the wood lining or tim-ber of the front post by the screws 36 through block K and also by screws 96 through plate 41, block K and into timber 34.

In constructing a reaction closed door, the buffer spring 62 is preferably mounted on a foot 63 formed of a sheet metal loop riveted to the channel-iron 2.

In case it is desired to use wooden front 125 and back posts, such posts may be substi-tuted for those shown.

64 designates a timber fitted against the channel-iron 2, flush with the sides thereof for nailing the back edge of the siding thereto. 130

65 designates upright stays connecting the members 2 and 42 of the header substantially in the manner shown in said application Serial No. 218,060. The sheet metal parts are 5 preferably secured together by rivets 66.

The back bracket support 5 is preferably formed of a single blank steel sheet of rectangular form slit and bent to form the side walls 68, bracket supporting projection 9, 10 laps 69 for sustaining the same and a head 70 for fastening the support to the header.

In Fig. 21 the solid lines 71 indicate the slits in the metal and the dotted lines 72 indicate the lines along which the bends are 15 made for forming the completed support.

73 designates the base to which the wall structure above described will be fastened. The same may be a board or timber temporarily secured to the metal frame for holding 20 the bottom of the door post during shipment, or it may be the floor of the building in which the structure is installed.

74 designates nails or screws through the anchor plates, fastening the frame to the 25 base.

By the construction herein described, the wall pocket structure of which the rail, its brackets and the adjuncts thereto are thus made component parts is given great rigidity 30 and strength with a minimum thickness of wall and at the same time the rail is made accessible and peculiarly adapted to adjustment and to removal and replacement.

When it is desired to remove the rail from 35 the structure, the set-screw 32 will be loosened and the stirrup 31 will be slid to the right beyond the bracket arm 24. Then the adjusting screw 25 may be screwed up, thus raising the bracket 21 until the screws 96 are 40 exposed; whereupon by unscrewing the same, the front bracket support 4 with the bracket 21 may be taken down, and thereupon the rail 12 may be withdrawn from its socket 29 and readily withdrawn from the wall pocket. 45 It may be replaced by reversing the operation just describing; it being an easy matter to place the back end of the rail over the bracket arm 14 and insert said rail end into the seat 29; to then replace the bracket 50 support 4 with the bracket 6 therein and secure it by the screws 96 and then bring the stirrup 31 into place and clamp it as before.

The boards for the fluted siding may be of 55 any suitable width. Preferably they are grooved or fluted to form three ridges; the edge ridge 75 being the same width, and the intermediate ridge 76 being twice that width and less in width than the grooves 77, respectively, so that when the boards are matched 60 together the siding will present ridges and grooves of uniform width, respectively.

By the construction shown, the mouth posts of the wall-pocket may be sufficiently rigid without requiring so great cross-sectional dimensions as is required in the mouth- 65

posts of the wall-pockets for sliding doors heretofore constructed. I have constructed in accordance with this invention, mouth-posts for wall pockets of a sliding door having an opening seven feet high, in which the 70 cross-sectional dimensions of each of the mouth-posts were two and one-quarter inches by one and one-half inches; and the same are more rigid than the former mouth-posts, the cross-sectional dimensions of which were 75 more than twice that stated. By this construction, therefore, I am enabled to use castings as narrow as three and one-quarter inches; and by means of the furring strips 53, the width may be increased indefinitely and 80 the stiffness is, of course increased by the addition of such furring strips. When the tongued and grooved siding is fixed in the channel-irons and nailed to the posts or the furring thereon as the case may be, the 85 rigidity of the wall is immediately increased; and with the addition of the lathing and cement or plaster applied thereto to finish the wall, the structure is more solid than it has heretofore been possible to construct a sliding door 90 wall-pocket structure, of like dimensions.

By making the wooden portions in sections an advantage is gained in that there is practically no liability of any such warping as can displace or interfere with the trueness of the 95 metal frame. The projections or portions 48 bent at right angles to the main bodies of the strips or straps 47 help greatly in adding stiffness to the posts. Some of said projections 48 are respectively furnished with a further bent portion 75 so as to embrace the lower end of the timber 49 which seats thereon. It is to be understood, however, that the invention is not strictly limited to a structure in which the reinforcing straps 47 and 100 the timbers 49 are in sections as shown.

It is to be observed that the mouth posts are the portions of a wall pocket structure that are most subject to strain; and that by constructing the same of angle iron with a reinforcement of strap iron 47 laid against the outer edge flange 76 of the angle iron upright, the angle iron may be made of the same thickness as the other parts of the sheet metal frame. The strap iron 47 and all the other 110 sheet metal portions of the frame are preferably of the same thickness and their widths are preferably the same as, or are aliquot parts or multiples of each other so that a sheet of metal of determined width made at 115 the rolling mill may be slit to the appropriate sizes for the several parts respectively, and then run through the necessary rolls respectively, to form the appropriate parts of the structure.

The slot screens 57 are desirably made of angle irons each having one of its flanges 77 perforated for screws or nails 78 by which it is fastened to the inner face of the head jamb 56 that is detachably mounted on the head 130

timber F by screws 79. When the head jamb is detached, the screen therefor may be fastened thereon either longitudinally or aslant and when the head jambs are in place the means by which the screens are fastened thereto, are completely concealed. The slot-screens 57 are oppositely arranged with a narrow slot between them, thus providing a slot immediately below the center of the rail, as clearly shown in Fig. 19, and each is provided with an upwardly extending perforated flange 77 by which it is fastened to the head jamb of the wall structure so that the means of fastening are concealed from view. The head stops 83 project underneath the joint between the head jambs 56 and the slot-screens so that said joint is concealed.

The bracket arms are wedge shape, widening from top edge downward and the edges of the trough shape sheet metal rail engage therewith and are sprung apart thereby when the pressure of the stirrup 30 is applied on the top of the rail. Thus all looseness is avoided.

By omitting the post A with channel-iron 1 the remainder of the structure is adapted for one-half of a double sliding door structure which may be formed by uniting a like half thereto by any suitable splicing not shown.

The intermediate ties 45 are desirably flat where the siding is used and the siding fits against it so as to be supported thereby; but it is to be understood that for metal latheing the angle-iron ties shown in said application No. 218,060 will be preferred.

80 is the back jamb, 81 the back stop and 82 the front stop.

The rail held in tension in the metal frame 40 forms a stay tending to hold the entire frame solid.

Claims.

1. A semi-metallic structure for sliding doors comprising external frame members of channel-iron to form a portion of the header and the front and back posts of the structure, means at the junctions of said header and said posts for supporting rail brackets, the same being fastened to the header and to their posts respectively and tying said header and posts together, each of said bracket supports being provided at the lower end with a projection for supporting its bracket, a loop at the upper portion of the back bracket support, a bridge on the supporting projection of said bracket support, a cantaliver bracket having a base which extends above and below its bracket arm, the upper extension of said bracket being provided with a perforation and inserted behind the loop, and the lower extension being interlocked with said bridge, a fastener through the loop the upper extension of the base and the bracket support and the back post, a shim above the fastener and between the upper bracket-base
2. A semi-metallic structure for sliding doors comprising external frame members of channel-iron to form a portion of the header and the front and back posts of the structure, means at the junctions of said header and said posts for supporting rail brackets, the same being fastened to the header and to their posts respectively and tying said header and posts together, each of said bracket supports being provided at the lower end with a projection for supporting its bracket, a loop at the upper portion of the back bracket-base

extension and the bracket support, a timber fastened in the channel of the front post channel-iron, a block fastened to the upper portion of said timber and supporting the front bracket support, a cantaliver bracket 70 for the front post mounted in said bracket-support, the same being provided with a base and having extensions of said base above and below its bracket arm, the lower extension having a vertical screw hole, an adjusting screw engaging the lower projection of the front bracket support and screwed into the lower extension of the bracket base, a loop over the upper extension of said base, a rail cramped in the rear bracket, and extending 80 over the front bracket, a stirrup over the front end of said rail provided with a set-screw for drawing the rail toward and clamping it to the arm of the front cantaliver bracket and for producing tension in the 85 rail, metal ties on opposite sides of the structure respectively, connecting the posts together below the channel iron member of the header, sheet metal mouth-posts on opposite sides of the structure and respectively fastened to said ties and to the header, ties connecting the mouth posts respectively to the back posts, re-inforcing sheet metal strips fastened to the mouth posts and provided with projections, said mouth posts and strips 95 being perforated, timbers held by said projections, nail's or screws extending through said mouth posts into said timbers, channel-iron ties at top and bottom of the mouth posts connecting the same with the back post, 100 the lower channel-iron tie having its channel upper-most and the upper channel-iron tie having its channel downward, longitudinally grooved siding fastened in place in said channels and against said timbers, brackets on 105 the door-way side of the mouth posts, brackets on the outer faces of the front post, head timbers mounted in said brackets on opposite sides of the frame, head jambs in said head timbers respectively, metal slot-screens 110 for said head jambs respectively, each comprising a metal blade fastened to and extending inward from the head-jamb to form a wall of a slot below the rail, and anchor plates extending across the bottom of the structure 115 frame and connecting the mouth post and lower channel tie of one side of the structure with those on the other side of the structure.

2. A semi-metallic structure for sliding doors comprising external frame members of channel-iron to form a portion of the header and the front and back posts of the structure, means at the junctions of said header and said posts for supporting rail brackets, the same being fastened to the header and to 120 their posts respectively and tying said header and posts together, each of said bracket supports being provided at the lower end with a projection for supporting its bracket, a loop at the upper portion of the back bracket-base

- support, a bridge on the supporting projection of said bracket support, a cantaliver bracket having a base which extends above and below its bracket arm, the upper extension of said bracket being provided with a perforation and inserted behind the loop, and the lower extension being interlocked with said bridge, a fastener through the loop the upper extension of the base and the bracket support and the back post, a shim above the fastener and between the upper bracket-base extension and the bracket support, a timber fastened in the channel of the front post channel-iron, a block fastened to the upper portion of said timber and supporting the front bracket, a cantaliver bracket for the front post, mounted in said bracket-support, the same being provided with a base and having extensions of said base above and below its bracket arm, the lower extension having a vertical screw hole, an adjusting screw engaging the lower projection of the front bracket support and screwed into the lower extension of the bracket base, a loop over the upper extension of said base, a rail crimped in the rear bracket and extending on the front bracket, a stirrup over the front end of said rail provided with a set-screw for drawing the rail toward and clamping it to the arm of the front cantaliver bracket and for producing tension in the rail, metal ties on opposite sides of the structure, respectively, connecting the posts together below the channel-iron member of the header, sheet metal mouth-posts on opposite sides of the structure and respectively fastened to said ties and to the header, ties connecting the mouth-posts respectively to the back post, re-inforcing sheet-metal strips fastened to the mouth posts and provided with projections, said mouth posts and strips being perforated, timbers held by said projections, nails or screws through said mouth posts into said timbers, channel-iron ties at top and bottom of the mouth posts connecting the same with the back post, the lower channel-iron tie having its channel uppermost and the upper channel-iron tie having its channel downward, longitudinally cut diagonally at its ends and fitted in the channels of said channel-iron stays and fastened in place against said timbers, lath fastened to the siding horizontally and metallic anchor plates fastening together the ties at bottom of the structure.
4. A semi-metallic wall-structure for sliding doors comprising external frame members formed of channel iron to form a portion of the header and the front and back posts of the structure, metal ties connecting the posts together below the channel-iron member of the header, sheet metal strips fastened to the mouth posts and provided with projections, said mouth posts being perforated, timbers held by said projections, nails or screws through said posts into said timbers, channel iron stays at top and bottom of the mouth posts connecting the same with the back posts, the lower channel iron stay having its channel upper-most and the upper channel iron stay having its channel downward, longitudinally fluted siding cut diagonally at its ends and fitted in the channels of said channel-iron stays and fastened in place against said timbers, lath fastened to the siding horizontally and metallic anchor plates fastening together the ties at bottom of the structure.
5. A semi-metallic wall-structure comprising a header and end posts fastened to the header and mouth posts consisting in upright angle-irons; an anchor plate fastening said angle-irons together at the bottom; reinforcing strips of sheet metal in the angles of said angle-iron posts and provided with projections for receiving timbers, timbers for the angles of said angle-iron posts supported by the projections and means fastening the timbers, the reinforcing strips and the angle-irons together.
6. A semi-metallic structure for sliding doors comprising external frame members formed of channel-iron and fastened together to form a portion of the header and the front and back posts of the structure, metal ties connecting the posts together below the channel-iron member of the header, sheet metal strips fastened to the mouth posts and provided with projections, said mouth posts being perforated, timbers held by said projections, nails or screws through said posts into said timbers, channel iron stays at top and bottom of the mouth posts connecting the same with the back posts, the lower channel iron stay having its channel upper-most and the upper channel iron stay having its channel downward, longitudinally fluted siding cut diagonally at its ends and fitted in the channels of said channel-iron stays and fastened in place against said timbers, lath fastened to the siding horizontally and metallic anchor plates fastening together the ties at bottom of the structure.

metal mouth posts fastened to said ties and to the header, ties connecting the mouth posts respectively to the back-post, re-inforcing sheet metal strips fastened to the 5 mouth posts and provided with projections, said mouth posts being perforated, timbers held by said projections, nails or screws through said posts into said timbers, channel-iron stays at top and bottom of the 10 mouth posts connecting the same with the back post, the lower channel-iron stay having its channel upper-most and the upper channel-iron stay having its channel downward, and siding fastened in place in said 15 channels and against said timbers.

7. In a wall structure for sliding doors, a post comprising an angle iron up-right and sectional re-inforcements therefor composed of sheet metal strips fastened thereto inside 20 the angle and bent transversely and thereby furnished with transverse projecting portions.

8. In a wall structure for sliding doors, a post comprising an angle iron up-right and 25 sectional re-inforcements therefor composed of sheet metal strips fastened thereto inside the angle and furnished with projections, and sectional timbers carried by said re-inforcing sections.

30 9. A semi-metallic wall structure for sliding doors comprising a channel-iron header, two channel-iron end posts fastened thereto, two angle iron mouth posts fastened to the head between the end posts and with a space 35 between them, a base to which all of the posts are fastened, metallic re-inforcing strips on the angle iron posts; metal bracket supports fastened in the channels of the channel iron posts beneath the head, brackets adjustably 40 mounted in said supports, and a rail carried thereby.

10. In a semi-metallic wall-pocket structure for sliding doors, a mouth-post comprising an angle iron upright reinforced by a 45 sheet metal strip in the angle, and a timber in the angle and against said strip.

11. In a semi-metallic wall-pocket structure for sliding doors, a mouth-post comprising an angle iron upright and strap iron 50 reinforcement both perforated, a stop and screws or nails therethrough substantially as set forth.

12. In a semi-metallic wall-pocket structure for sliding doors, a mouth-post comprising an angle iron upright and strap-iron 55 reinforcement in the angle-iron bent crosswise and thereby provided with transverse projections.

13. In a semi-metallic wall-pocket structure for sliding doors, a mouth post comprising an angle iron upright and strap-iron reinforcement in sections, each section having 60 bent portions and supporting each other substantially as set forth.

65 14. In a semi-metallic wall-pocket struc-

ture for sliding doors, the combination with the frame, of cantaliver rail-brackets fastened to said frame, a rail cramped on one of the brackets and resting on the tip of the other bracket, with an open space between 70 its end and the bracket a stirrup around the rail and said other bracket and means underneath the bracket engaging such bracket and stirrup for drawing the end of the rail down toward such bracket. 75

15. In a wall-pocket structure for sliding doors the combination with a rail and a cantaliver bracket therefor, the bracket being aslant with an open space between the 80 bracket and the end of the rail, of a stirrup and means underneath the bracket engaging the stirrup and bracket for drawing the rail toward the bracket.

16. In a wall-pocket structure, for sliding doors the combination with a rail and a 85 bracket therefor, the bracket being aslant with an open space above, of means engaging the top of the rail and the under face of the bracket, for forcing the rail toward the bracket. 90

17. In a wall-pocket structure, the combination with a rail and a support for one end thereof of a bracket mounted for supporting the other end of the rail, means for adjusting said bracket, and means for clamping the 95 end of the rail to such bracket.

18. In a wall-pocket structure for sliding doors, the combination of a cantaliver bracket fastened to the frame of the structure and provided with a rail seat to engage 100 the top of the inner end of the rail at the base of the bracket, a rail resting on the tip of the bracket and having an end engaged in said seat, another bracket fastened to the frame of the structure, and adjustable means for 105 holding the other end of the rail in tension on the other bracket.

19. In a wall-pocket structure for sliding doors, a bracket for the inner end of the rail, a rail engaged at top and bottom by, and 110 thereby cramped in said bracket, a cantaliver bracket for the other end of the rail and means for adjusting the tension on the end of the rail held by said cantaliver bracket.

20. In a wall-pocket structure for sliding 115 doors the combination with a rail held cramped by engagement at top and bottom with a support at the inner end of the pocket, of an adjustable bracket for the other end of the rail and means for detachably fastening 120 the rail to said bracket.

21. A wall pocket structure comprising a metallic frame having channel-iron ties above and below, and siding, the upper and lower edges of which are in the channels of 125 said ties.

22. A wall pocket structure comprising a metallic frame having upper and lower channel-iron ties and fluted siding having its edges in the channels of said ties. 130

23. A wall structure comprising a metallic frame having channel-iron ties, fluted siding having edges in said ties and lathing on the fluted faces of said siding.
- 5 24. A wall structure comprising a metallic frame having channel-iron ties, siding having edges in said channel-iron ties and composed of longitudinally grooved members and lathing on the grooved face of said siding.
- 10 25. A wall structure comprising a frame having channel-irons, siding composed of longitudinally fluted boards cut aslant at their ends and arranged aslant in the frame, the upper and lower edges of said siding being in said channel-irons.
- 15 26. A wall structure comprising a frame having channel-irons, siding composed of longitudinally fluted boards cut aslant at their ends and arranged aslant in the frame with upper and lower edges of said siding in said channel-irons and wooden lath fastened horizontally on the fluted face of said siding.
- 20 27. A wall structure comprising a metallic frame composed of up-right posts and ties between said posts, the upper and lower ties being channel-irons, timbers fastened to said posts, and siding composed of boards cut aslant at their ends and set aslant in the frame and fastened to said timbers and in said channel-irons.
- 25 28. A wall pocket structure comprising metallic posts and channel-iron ties, timbers fastened to said posts, and fluted siding fastened to said timbers and in said channel-irons.
- 30 29. A wall structure comprising metallic posts and channel-iron ties, siding composed of longitudinally fluted boards cut aslant at their ends and set aslant between the posts and fastened to the timbers and in the channel-irons and lathing on the fluted face of said siding.
- 35 30. A wall pocket structure comprising a metallic frame having posts, upper and lower channel-iron ties, one or more intermediate flat ties and siding fastened to the posts and in the channel-irons.
- 40 31. A wall structure comprising a metallic frame having posts, upper and lower channel-iron ties, one or more intermediate flat ties, siding composed of longitudinally fluted boards cut aslant at their ends and fastened to the posts and in the channel-irons and resting against the intermediate tie or ties.
- 45 32. A wall pocket structure comprising a metallic frame having posts, upper and lower channel-iron ties and one or more intermediate flat ties, and siding fastened to the posts and in the channel-irons and resting against the intermediate tie or ties.
- 50 33. A semi-metallic structure for sliding doors comprising external frame members fastened together to form a portion of the header and the front and back posts of the structure, metal ties connecting the posts together, sheet metal mouth posts fastened to said ties and to the header, ties connecting the mouth posts respectively to the back-post, re-inforcing sheet metal strips fastened to the mouth posts and provided with projections, said mouth posts being perforated, timbers held by said projections, nails or screws through said mouth posts into said timbers, ties at top and bottom of the mouth posts connecting the same with the back post, and siding fastened in place against said ties and timbers.
- 55 34. A semi-metallic structure for sliding doors comprising external frame members fastened together to form a portion of the header and the front and back posts of the structure, ties connecting the posts together, angle-iron up-rights for mouth-posts fastened to said ties and to the header, ties connecting the mouth-post uprights respectively to the back post, timbers fastened in the angles of said mouth-post up-rights and siding fastened in place against said ties and timbers.
- 60 35. In a wall structure for sliding doors, a mouth-post comprising an angle iron up-right and timber reinforcement therefor fastened thereto inside the angle.
- 65 36. In a wall structure for sliding doors, a post comprising an angle iron up-right and sectional re-inforcement therefor fastened thereto inside the angle.
- 70 37. A semi-metallic wall structure for sliding doors comprising a channel-iron head, two channel-iron end posts fastened thereto, two angle iron mouth posts fastened to the head between the end posts and with a space between them, a base to which all of the posts are fastened, metal bracket supports fastened in the channels of the channel iron posts beneath the head, brackets mounted in said supports, and a rail held in tension thereon.
- 75 38. A semi-metallic wall-structure comprising a header, end posts fastened to the header, mouth posts comprising upright angle-irons, an anchor plate fastening said angle-irons together at the bottom, reinforcing strips of sheet metal in the angles of said angle-iron posts and provided with projections for receiving timbers, timbers for the angles of said angle-iron posts supported by the projections, means fastening the timbers, the reinforcing strips and the angle-irons together, a rail connected with said end posts, and means for holding the rail in tension.
- 80 39. A semi-metallic wall-structure comprising a header, end posts, fastened to the header, mouth-posts comprising up-right angle-irons, means fastening said angle-irons together at the bottom, timbers fastened in the angles of the angle-irons, a rail connected with said end posts, and means for holding the rail in tension.
- 85 40. In a wall pocket structure for sliding doors, an angle-iron slot-screen having a per-

forated flange extending upward from the screen and fastened to the inner wall of the structure.

41. In a wall pocket structure for sliding doors oppositely arranged sheet metal slot-screens having a narrow slot between them.

42. In a wall pocket structure for sliding doors, the combination with a trough shaped rail and a bracket therefor chambered thereto in and resting on the tip of said bracket with

an open space between the bracket and the end of the rail, of means engaging the top of the rail and the under-face of the bracket for forcing the end of the rail toward the bracket.

Signed at Bridgeport, Connecticut, January 28, 1905.

DANIEL SCHUYLER.
